UNITED STATES PATENT OFFICE.

JULIUS E. WILL AND HENRY WILL, OF BETHEL, MISSOURI, ASSIGNEES OF
ONE-THIRD TO PHILIP STEINBACH, SR., OF SAME PLACE.

HAY-STACKER.

SPECIFICATION forming part of Letters Patent No. 399,106, dated March 5, 1889.

Application filed October 2, 1888. Serial No. 287,052. (No model.)

To all whom it may concern:

Be it known that we, JULIUS E. WILL and HENRY WILL, of Bethel, in the county of Shelby and State of Missouri, have invented 5 certain new and useful Improvements in Hay-Stackers; and we do hereby declare the following to be a full, clear, and exact description of the invention, such as will enable others skilled in the art to which it pertains 10 to make and use it, reference being had to the accompanying drawings, which form part of this specification.

Our invention relates to an improvement in hay-stackers; and it consists in the combination 15 of a suitable supporting-frame, braces or supports which extend therefrom, the hay-fork which is pivoted in the supports, a counter-weight which is secured to the fork, and an operating-cord by means of which the fork 20 is raised so as to dump its load upon the stack, as will be more fully described, and pointed out in the claims.

The object of our invention is to provide a machine by means of which the hay can be 25 raised from the ground and deposited upon the stack which is being formed with ease and rapidity.

Figure 1 is a side elevation of a hay-stacker which embodies our invention, the parts being shown in solid lines and in another position in dotted lines. Fig. 2 is a plan view of 30 the same. Fig. 3 is a perspective of a hay-stacker which embodies our invention.

A represents a suitable rectangular frame 35 upon which the stacker is placed, and which, when in operation, is to be placed upon a wagon-gear or other suitable support. This frame is braced together in any way that may be preferred, as we do not restrict our invention in this respect. Rising from this frame

40 A at a suitable inclination are the two sets of braces B C, which are united together at their upper ends by the pivotal bolt D, upon which the hay-stacker moves. The two front braces, 45 B, are secured at their lower ends inside of the frame A, while the lower ends of the braces C are secured to the outer side. By this construction the braces B are placed in the line of travel of the stops E, secured to the levers 50 F, for the purpose of limiting the distance that the fork G shall be moved upward and

backward. Extending across the under side of the frame A is the cross-brace H, to the ends of which are secured the braces I, which are inclined upward at a suitable inclination 55 and are fastened at their upper ends to the outer sides of the braces C for the purpose of supporting the two sets of braces B C rigidly in position.

The two levers F, pivoted upon the pivotal 60 bolt D, have the hay-fork G secured to their front ends. This hay-fork G consists of two sets of teeth, a b, which are placed at an angle to each other, as shown, and in between which the hay which is to be deposited upon 65 the stack is placed. This hay may be delivered directly from the hay-fork, or may be thrown upon the lower set of teeth by hand. The lower set of teeth, a, which are the longest, serves to receive the hay direct, while the 70 second set, b, which are somewhat shorter and are placed at a suitable angle to the lower set, extend at any suitable angle thereto, so as to catch the hay and hold it while being elevated.

If it was not for the second set of teeth, b, placed at a suitable angle after the fork was 75 raised to a certain position, the hay would begin to drop from the teeth a upon the wagon instead of being delivered upon the stack.

The two sets of teeth which form the hay-fork are secured directly to the two levers F, and to the side braces, J, which are secured to the levers F by means of the two cross-bars K, which extend across the tops of the levers 80 and project beyond their sides, and the two braces L. The two braces L are secured to the upper set of teeth, and to the front cross-bar, K, and these braces L are provided with a series of holes, so that the angle at which 85 the upper set of teeth are placed in relation to the lower one may be varied at will.

For the purpose of varying the angle at which the two sets of teeth are placed to each other, the upper set is pivoted at the lower 90 ends to the stationary set, and then the upper set is made adjustable by means of the braces L. Projecting from the under side of the levers F are the braces N, and projecting from the cross-piece O, which extends across 100 the rear ends of the levers F, is a brace, P, which is secured at its lower end to the two

braces N. The braces P N form a triangle, of which the levers F form the third side, and the brace P is strengthened in position by the braces Q, which project downward from the 5 under side of the levers F. To the upper end of the brace P is secured the stationary end of the operating-rope R, which passes down under the lower end of the brace, then forward around the pulley S upon the front 10 cross-piece of the frame A, then back under the pulley T upon the lower end of the brace P, up over the movable pulley U, fastened to the upper end of the brace, then down under the pulley V upon the lower end of the brace 15 P, and then forward past the pulley W upon the cross-bar to which the pulley S is attached. For the purpose of counterbalancing the hay-fork and to cause the fork to return to position, a suitable weight, X, is secured to 20 the braces N and P at their junction, and this weight serves to counterbalance the fork after it has been raised into the position shown in dotted lines in Fig. 1, so as to cause the fork to begin to return to position as soon as 25 the rope is slackened for that purpose. After the weight has returned to a vertical position as the fork descends, it then begins to act as a counter-weight to the fork, so as to prevent the fork descending with a rush and 30 striking the ground with sufficient force to break the machine. In proportion as the fork descends after the weight passes its vertical point the fork must raise the weight by means of the braces N P, and this upward movement of the weight checks the 35 descent of the fork correspondingly. After the fork has been raised to the full distance which it is intended it shall move, as shown in dotted lines, the stops E strike against the 40 brace B, and then all further movement of the fork toward the stack is checked. After the fork has been moved the full distance, the hay drops from between the two sets of teeth which form the fork and falls upon the stack. After 45 the fork has been loaded, it is only necessary to start the animal fastened to the elevating-rope R, when the load will be raised and deposited upon the stack without any further trouble upon the part of the operator. To 50 prevent the fork from striking against the

ground as it returns to position, the ends of the side braces, J, are made to project through the teeth of the fork sufficiently far to strike against the ground, and thus receive all of the shock.

We are aware that sliding weights have heretofore been used in connection with hay-stackers and placed upon ropes connected with the fork portion, and this we disclaim. Our invention differs from this in using a stationary 60 weight, X, which is secured rigidly to the extreme end of the frame away from the fork, so that it will be in position to first start the fork-levers in returning to position as soon as the load is dumped, and then serve to arrest 65 the downward movement of the parts by its gravity.

Having thus described our invention, we claim—

1. The combination of a suitable supporting-frame, the levers F, the fork composed of two sets of teeth placed at a suitable angle to each other, the braces N P, secured to the levers, a weight secured rigidly to the brace, suitable guiding-pulleys, and the operating-rope, substantially as described. 70

2. In a hay-stacker, the combination of the levers F, pivoted upon a suitable supporting-frame, the braces J, cross-pieces K, and the adjustable braces L, with the hay-fork consisting of a stationary set of teeth and a pivoted shorter set of teeth, which are adapted to be held at different angles to the stationary set by means of said braces L, substantially as set forth. 80

3. The combination of the frame A, the braces B C, secured together at their upper ends by the cross-bolt D, the levers F, having the fork G secured to their front ends, the stops E, secured to the rear ends of the levers, the braces N P, the weight secured to the braces, the guiding-pulleys, and the operating-rope, substantially as specified. 85

In testimony whereof we affix our signatures in presence of two witnesses.

JULIUS E. WILL.
HENRY WILL.
